CLAIM

The ornamental design for a confectionery bottle, as shown and described.

DESCRIPTION

FIG. 1 is an enlarged perspective view of a confectionery bottle, showing our new design;

FIG. 2 is a front view thereof;

FIG. 3 is a back view thereof;

FIG. 4 is a side view thereof;

FIG. 5 is another side view thereof;

FIG. 6 is a top view thereof; and,

FIG. 7 is an enlarged bottom view thereof.

The broken lines shown illustrate portions of the confectionery bottle and form no part of the claimed design.
